WILLIAM H. GOLDSMITH, JR., OF BIDDEFORD, MAINE, ASSIGNOR TO SACO-LOWELL SHOPS, OF BOSTON, MASSACHUSETTS, A CORPORATION OF MASSACHUSETTS.

THREAD-GUIDING MECHANISM

1,210,641.

Specification of Letters Patent. Patented Jan. 2, 1917.

Application filed December 5, 1914. Serial No. 875,709.

To all whom it may concern:

Be it known that I, WILLIAM H. GOLDSMITH, Jr., of Biddeford, in the county of York and State of Maine, a citizen of the United States, have invented a new and useful Improvement in Thread-Guiding Mechanisms, of which the following is a full, clear, and exact description, reference being had to the accompanying drawings, forming a part of this specification, in explaining its nature.

The present invention relates to an improvement in thread guiding mechanisms especially those designed for spinning and twisting machines.

The essential object of my invention is to provide a thread guiding mechanism of finished structure possessing all the advantages to be derived from a simple, compact and rigid construction, which is easily controlled and which can easily be kept clean.

The mechanism can best be seen and understood by reference to the drawings in which—

25 Figure 1 is a plan showing the application of the mechanism to the frame of a spinning machine, that portion of the frame only being shown which is necessary to a proper understanding of the present invention. Fig. 2 is a view mainly in side elevation but partly in section of the structure shown in Fig. 1. Fig. 3 is a section on the line 3—3 of Fig. 1. Fig. 4 is a plan of the under side of a portion of the mechanism to 30 which special reference will hereinafter be made. Fig. 5 is a section on the line 5—5 of Fig. 3. Fig. 6 is a front elevation of a portion of the mechanism to which special reference will hereinafter be made. Fig. 7 is a plan of a slightly modified structure, and Fig. 8 shows mainly a side elevation thereof.

Referring to the drawings:—1 represents a portion of a roller beam which forms a part of a spinning or twisting machine and which customarily as in the present case provides a fixed primary support for the thread guides.

2 represents the holder of a guide wire and
3 the guide wire.
50 4 represents a secondary support carried
by the primary supporting beam and to
which the holders are hinged or otherwise
pivotally secured. This secondary support
is mounted to turn in order that a series of

holders and guide wires may be held by it in a proper operative or substantially horizontal position or be turned collectively by the turning of the support and held in a substantially vertical or upright position for dosing.

The parts being thus generally referred to, reference will now be made in further detail to the various elements and first with relation to the secondary supporting member 4 and mounting therefor. This member 65 preferably comprises a rigid bar mounted to turn in bearings 5 carried by brackets 6 secured by suitable fastenings 7 to the front side or face of the roller beam. The supporting bar 4 in that part which turns with 70 in the bearings is made circular in form, and in this same connection it will be understood that as many of the bearings 5 and supporting brackets are provided as will insure the proper support of the bar. That portion or 75 portions of the bar, however, which lies between the respective bearings and to which the holders are secured, as will later be explained, is made semi-circular in cross section whereby it may present a flat under side 80 or face 8 which when the bar is in its normal position will occupy a substantially horizontal plane (see Figs. 1 and 3).

The supporting bar 4 is provided at its end with a stop 9 which defines the limits within which the bar may turn and which limits correspond with the turned positions of the holders and guide wires as above referred to. The stop 9 consists of a hub 10 secured to the end of the bar and from which project arms 11 and 12, respectively. Of these arms the arm 11 is adapted to engage the front side or face of the roller beam when the bar has been turned forward so that the holders and guide wires will occupy their proper operative or substantially horizontal positions, while the arm 12 is adapted to engage the top side of the roller beam when the bar has been turned backward elevating the holders and guide wires into a substantially vertical or upright position preliminary to doffing as aforesaid. It will be further observed that either the arm 11 or the arm 12 forms a crank by which the bar can be turned, which function is availed of by providing the arm 12 with a handle 13 (see Fig. 2).

The holders are each secured to the bar 4

by a leaf 15. This leaf comprises a plate fixed to the under side or face 8 of the bar 4 preferably by spot-welding. The leaf is provided with dependent side flanges 16 the front ends 17 of which project forward beyond the front edge of the leaf and bar (see Figs. 3 and 4).

The holder 2 comprises in part a top plate 18 having dependent side flanges 19. The plate 18 has a rear extension or tail portion 20 which is extended to lie beneath the leaf and has bearing against the under side thereof. The flanges 19 of the plate and extension 20 thereof extend by the inner sides 15 to the flanges 16 of the leaf, fitting snugly between these flanges, which accordingly operate to hold the entire holder in place against lateral displacement (see Fig. 4).

In order that each holder may be turned individually from a substantially horizontal operative position to an upright or vertical position in its relation to the bar 4, a hinged connection is made between the holder and leaf by a hinge-pin 22 which extends beneath the top plate 18 through the flanges 19 thereof and also through the projecting ends 17 of the flanges of the leaf. The hinge-pin 22 lies forward of the front edge of the leaf and bar 4, the rear extension 20 of the plate 18 extending backward from the point of the hinged connection to lie beneath the leaf and bear against the same as aforesaid (see Figs. 3 and 4). This enables the holder to be turned from a substantially horizontal operative position to an upright or vertical position, the end extension or tail portion 20 then turning downward away from the leaf against which it is bearing, while the main body of the holder 40 and guide wires carried by it turns upward. In this connection it will be understood that the holder is maintained in its normally operative or substantially horizontal position by the bearing of the tail portion 20 of the holder against the under side of the leaf.

The hinge-pin is concealed on the under side of the holder by a bottom plate 25 which fits within the flanges 19 of the top plate and extends back over the hinge-pin and has the flange 26 thereof extended upwardly around the pin from the rear end of the plate (see Fig. 3). The bottom plate is held in place by the flanges of the top plate, the bottom edges 27 of these flanges being bent inwardly to embrace the bottom plate (see Fig. 5).

The guide wire 3 is adjustably secured to the holder by a bolt and nut in a manner commonly employed. The rear end of the guide wire is turned to form an elongated loop 30 which is contained within the chamber of the holder between its top plate 18 and the bottom plate 25. A bolt 31 extends through the top plate, loop 30 and bottom

plate. On the end of this bolt is a nut 32 which, when tightened to bear against the bottom plate, clamps the looped end of the guide wire between the respective plates and thereby securely fixes the wire to the holder, permitting, however, of the adjustment thereof upon releasing the nut (see Figs. 3 and 4). In order that the shank of the guide wire may be moved laterally on the holder during the adjustment of the wire, the top plate has no dependent flange at the front edge thereof, which accordingly leaves a relatively wide opening in the front of the holder and through which opening the guide wire extends (see Fig. 6). The following provision is made for closing this opening: The front edge of the holder in which the opening is left is round to describe a half circle about the bolt 31 as a center, according to the plan shown in Fig. 1. Seated within the chamber of the holder is a plate 34 of generally segmental form through which the bolt passes. The plate 34 extends forward into the fore part of the chamber of the holder and is provided with a flange 35 forming a guard which covers the opening left in the holder. The guide wire passes through this guard, an opening being formed in the guard of just sufficient size to admit of the passage of the wire. The guard is rounded to conform to the interior of the semi-circular front of the holder and is of sufficient extent to cover the opening therein at all times whatever the laterally-adjusted position of the guide wire may be. In other words, as the guide wire is moved laterally within the opening left in the holder the guard will move with it around the bolt 31 as a center with the effect that a closure of the opening will be obtained at all times whatever the laterally-adjusted position of the guide wire may be (see Fig. 6).

In Figs. 7 and 8 there is shown a slightly modified construction especially with relation to the manner in which the holder is attached to and otherwise co-operates with the attaching leaf which secures the holder to the holder bar. In this modified construction the leaf 15 has no dependent flanges, nor is the top plate of the holder extended beneath the leaf. Instead, a top plate 18^a is provided which is hinged directly to the front edge of the leaf by a hinge-pin 22^a. The top plate is provided with dependent side flanges 19^a the bottom edges of which are turned at 27^a to embrace a bottom plate 25^a the same as before. The bottom plate 25^a is provided with upwardly-extending side flanges 37 and the plate together with its flanges is extended backward by extensions 20^a beyond the hinged connection to bear against the under side of the leaf 15 for maintaining the holder and guide wire in their operative substantially horizontal position. This modified construction

operates substantially the same as that first described and in other respects than those above indicated is substantially the same.

Having thus fully described my invention, 5 I claim and desire to secure by Letters Patent of the United States:—

1. A thread-guiding mechanism comprising a back supporting member presenting an under side, a leaf of sheet metal secured to the under side of said member, a guide wire, a sheet metal holder for the guide wire having hinged connection with said leaf, said holder having a sheet metal extension projecting backward beyond the point of its 5 hinged connection with the leaf to have bearing upwardly against the under side of the leaf for supporting the holder in an operative position.

2. A thread-guiding mechanism comprising a substantially half round bar, means for supporting said bar whereby the flattened side or face thereof will form the bottom side of the bar and lie in a substantially horizontal plane, a leaf of sheet metal secured to the under side of the bar, a guide wire, a holder of sheet metal bearing the guide wire and having hinged connection with said leaf, said holder being provided with a sheet metal extension projecting backward beyond the point of the hinged connection between the holder and the leaf and bearing upwardly against the under side of the leaf for supporting the holder in an operative position.

3. In a thread-guiding mechanism, the combination with a fixed primary support, of a secondary support comprising a bar presenting a flattened under side or face, bearings borne by the primary support with 40 in which the bar is turned, a sheet metal leaf secured to the under side of said bar, a guide wire, a sheet metal holder for the guide wire having hinged connection with the leaf, said holder being provided with a sheet metal extension projecting backward beyond the point of the hinged connection between the holder and the leaf to have bearing upwardly against the under side of the leaf for supporting the holder in an operative position.

4. A thread-guiding mechanism comprising a back supporting member presenting an under side or face, a sheet metal leaf secured to the under side of said member, a guide wire, a sheet metal holder for the guide wire having top and bottom plates, the top one of which plates makes hinged connection with said leaf and one of which plates is extended backward beyond the 50 point of said hinged connection to bear upwardly against the under side of the leaf for supporting the holder in an operative posi-

tion, and means for obtaining the hinged connection between said plate and leaf.

5. In a thread-guiding mechanism, the combination comprising a back supporting member presenting an under side or face, a sheet metal leaf secured to the under side of said member, said leaf having depending side flanges, a guide wire, a holder for the 70 guide wire comprising a sheet metal plate having depending side flanges coöperating with the side flanges of said leaf, a hinge-pin extending through the depending flanges of said plate and leaf to form a hinged connection between the same, said plate extending in part beyond said hinged connection to have bearing upwardly against the under side of said leaf for supporting the holder in an operative position.

6. A thread guiding mechanism comprising in combination an attachable leaf, a guide wire, a holder therefor having top and bottom plates, and a hinge wire coöperating with said top plate and leaf to form 85 a hinged connection for said parts, said top plate extending backward beyond the hinge wire to bear against the under side of said leaf, the bottom one of said plates to the holder being extended backward and covering said hinge wire on the under side of said holder.

7. In a thread guiding mechanism, the combination with an attaching leaf, of a guide wire, a holder therefor making hinged 95 connection with said leaf and thence extending backward beyond the point of said hinged connection to bear against the under side of said leaf, said holder comprising top and bottom plates, the top one of said plates 100 having dependent side flanges, said bottom plate being interposed between said flanges of the top plate and extending backward to cover said hinged connection on the under side of said holder.

8. In a thread guiding mechanism, the combination with a guide wire, of a holder therefor, said holder comprising spaced top and bottom plates with the end of the wire contained in the chamber between said 110 plates, said holder having a front edge with an opening therein, a member located within the chamber of said holder and provided with a turned edge forming a guard closing said opening and through which guard said 115 guide wire extends, means for retaining said guide wire, the same comprising a bolt passing through said plates and member and around which bolt said member and guard carried thereby is adapted to turn pivotally.
